FABRICATED BOBBIN RELEASER FOR WEFT
REPLENISHING LOOMSWilliam A. Blanchard, Millbury, Mass., assignor
to Crompton & Knowles Loom Works, Worcester,
Mass., a corporation of Massachusetts

Application December 14, 1948, Serial No. 65,243

16 Claims. (Cl. 139—232)

1

This invention relates to improvements in bobbin releasers of the type more generally employed on multicolor weft replenishing looms and it is the general object of the invention to provide a releaser of simple form which can be made cheaply and efficiently.

Multicolor weft replenishing mechanisms ordinarily employ a plurality of stacks of bobbins each having a bobbin delivering cradle at the lower end thereof. These cradles are controlled by releasers which are normally at rest but which upon call for replenishment have a vertical reciprocating movement the effect of which is to roll the cradle in such manner that the lowest bobbin of the associated stack is delivered from the latter and moved to a common transfer position. In the past these bobbin releasers have been expensive to make and have been of diverse forms requiring a number of different setting-up operations for their manufacture.

It is an important object of the present invention to provide a bobbin releaser made essentially of two parts which can be made as stampings and then assembled and interconnected in such manner as to form a complete releaser.

It is another object of the invention to provide one of the two parts which form the releaser with a recess to receive a portion of the other part, thereby causing correct registry of the two parts.

It is a still further object of the invention to provide a simple improved form of operating pawl or dog for the upper end of the releaser.

In order to simplify the manufacture of the releasers needed for a complete bobbin magazine it is a further object of the invention to provide a set of releaser forming elements which can be assembled in various ways to form a full complement of releasers.

With these and other objects in view which will appear as the description proceeds, the invention resides in the combination and arrangement of parts hereinafter described and set forth.

In the accompanying drawings, wherein a convenient embodiment of the invention is set forth,

Fig. 1 shows a side elevation of a multicolor weft replenishing loom as viewed from the center of the loom having the improved releasers applied thereto.

Fig. 2 is a top plan view of one of the releasers looking in the direction of arrow 2, Fig. 1.

Fig. 3 is a vertical section on line 3—3 of Fig. 2.

Fig. 4 is a perspective view showing a relatively long type of releaser employed in the mechanism set forth in Fig. 1.

2

Fig. 5 is a perspective view showing a relatively short type of releaser.

Fig. 6 is a bracketed view showing at the left a side or end elevation and at the right a front elevation of one of the shorter releaser forming parts or elements.

Fig. 7 is a view similar to Fig. 6, but showing the other part or element to be combined with the part shown in Fig. 6.

10 Fig. 8 is a view similar to Fig. 6, but showing a part or element for a longer releaser.

Fig. 9 is a view similar to Fig. 6, but showing an element or part to be combined with the part shown in Fig. 8.

15 Fig. 10 is a bracketed view showing at the left the blank for the dog or pawl for the upper end of the releaser and showing at the right a front elevation of the dog, and

Fig. 11 is an enlarged detail vertical section on line 11—11, Fig. 1.

Referring more particularly to Fig. 1, the multi-stack magazine designated generally at M is supported by a foot 11 secured in any approved manner to the loom frame 12. The magazine in

25 the present instance is provided with four stacks of bobbins which reading from the front or right of Fig. 1 rearwardly are designated at 13, 14, 15 and 16. At the bottom of each stack is located a rockable cradle part of which is designated at

30 17. These cradles are ordinarily empty, but upon call for a replenishing operation the cradle corresponding to the weft to be replenished is first

35 rocked in one direction to receive a bobbin and then rocked in the opposite direction to deliver the bobbin so that it may move to a common transfer position indicated at 18.

The magazine M includes in its construction a so-called color slide 20 including a rod 21 horizontally slidable on the magazine and connected

40 as at 22 to the upper arm 23 of a selector lever 24 pivoted at 25 to some part of the magazine. By means of a rod 26 which moves in timed re-

45 lation with the shifting shuttle boxes at the opposite end of the loom the color slide is moved horizontally to any one of four positions. The

color slide has front and back lifting and de-

45 pressing fingers 30 and 31, respectively, which are so related that they register with the stacks one

50 at a time, depending upon their longitudinal po-

55 sition. When a weft replenishing operation is initiated a rod 32 is lowered for the purpose of

lifting the fingers, and at a later time in the loom

cycle rod 32 depresses the fingers. It is by this

55 oscillation of the color slide that the cradle cor-

responding to the depleted shuttle is rocked first in one direction and then the other.

Extending above the color slide is a rocker shaft 35 the forward end of which is connected to a depending rod 36 operatively connected to the latch 37 of a transerrer arm 38. Under normal conditions the rocker shaft 35 is at rest, but when the fingers 30 and 31 have a downward movement incident to a replenishing operation shaft 35 is rocked to lift the latch 37 into transfer position.

The matter thus far described is of well known construction and of itself forms no part of the present invention and may be as set forth for instance in Patent No. 1,030,748.

In carrying the present invention into effect improved bobbin releasers are provided to rock the cradles and the shaft 35 when the fingers 30 and 31 operate as already described. These releasers, one for each stack and cradle, are designated in Fig. 1 at 40, 41, 42 and 43, and correspond respectively to bobbin stacks 13-16. As shown in Fig. 1, the front and back releasers 40 and 43, respectively, are relatively long, while the intermediate cradles 41 and 42 are shorter, and it will be also noted that the cradle operating wings 45 and 48 of the long releasers are of opposite hand and that the wings 46 and 47 of the shorter releasers are also of opposite hand. The four releasers are assembled from the four releaser forming parts or elements shown in Figs. 6 to 9.

Referring particularly to Figs. 6 and 7, there are provided two short elements 50 and 51 for making the short releasers 41 and 42. These elements are both flat and may be made of sheet metal, element 50 having a lateral arm 52 at the upper end thereof extending to the right, see Fig. 6, and having therebelow two operating fingers 53 and 54 extending to the left. As shown at the right hand part of Fig. 6 the element 50 is provided with an integral cradle operating wing member designated herein at 55 which is in the plane of the member 50. This wing member has an operating slot 56 to receive part of a bobbin cradle. Referring to Fig. 7, it will be seen that element 51 is also made of flat sheet metal and has a right hand lateral arm 57 and two left hand fingers 58 and 59. The lower end of element 51 differs from the lower end of element 50 in that it has no wing member but does have a notch or recess 60.

These two elements 50 and 51 can be used for making both of the short releasers 41 and 42. When it is desired for instance to make the short releaser 41 the element 50 will be located to the right of the element 51 as shown at the left of Fig. 7 and the wing member 55 bent to the left along line *a*, Fig. 6, part of the wing member entering the notch 60. The elements 50 and 51 are then secured together, as by brazing or welding. The wing member will then form the wing 46 for releaser 41. If, on the other hand, it is desired to form the releaser 42, element 50 is placed to the left of element 51 and the wing member 55 bent over the lower end of element 51 to the right. These two operations will provide the releasers 41 and 42 with their cradle operating wings disposed in opposite directions. When the short releasers are assembled as described and placed in the magazine the upper lifting fingers 53 and 58 will lie side by side in position to cooperate one at a time with the lifter fingers 30 and 31. This will also be true for the lower fingers 54 and 59.

Fig. 8 shows an element 62 for forming part of a long releaser, the upper part of this element being similar to element 50, but the intermediate part thereof being provided with notches 63 and 64. The lower part of element 62 is provided with a cradle operating wing member 65 similar to wing member 55 and having a slot 66 similar to slot 56.

The other long element 67 shown in Fig. 9 has its upper end formed as are the upper ends of the other elements, but the lifting fingers, instead of being relatively short as in Figs. 6 and 7, are relatively long because of the fact that these fingers must be offset from their respective releasers in order to cooperate properly with the lifting fingers 30 and 31. The upper and lower fingers 68 and 69, respectively, of element 67 are adapted to enter the notches 63 and 64, respectively, and the lower end of element 67 is notched as at 70 in the same way as is the lower end of element 51.

When forming the front long releaser 40 element 62 will be located at the left of element 67 as the latter appear at the right hand part of Fig. 9 and wing member 65 will then be bent to the right along line *a* through notch 70. The lifter fingers 68 and 69 will then be bent to the left along lines *b*, Fig. 9, to occupy notches 63 and 64, respectively. At a subsequent operation the fingers 68 and 69 are given a second bend along line *c* to provide finger ends 72 and 73. When releaser 43 is formed element 62 will be at the right of element 67 and the reverse operations are performed with respect to the wing member 65 and fingers 68 and 69.

After the parts have been assembled and secured to each other as described the next step in the manufacture of the releasers will be to drill spring receiving holes 76, see Fig. 3, and drill pin receiving holes 77, see Fig. 2.

Each releaser must be provided with a pawl or dog for operation of the rocker shaft 35. These dogs are all alike and are made as shown in Fig. 10. A flat blank 80 is formed as indicated at the left of Fig. 10 and has an intermediate bridge 81 from which extend right and left wings 82 and 83, respectively, each punched with a hole 84 and each provided with a spring retaining finger 85.

When forming the dog the ends of the wings 80 are bent at right angles to the blank 80 to the same side thereof along lines *d*, and fingers 85 are then bent up along lines *e* to be parallel to the blank. Wings 82 and 83 are then bent at right angles to bridge 81 to the same side thereof along lines *f* and *g*, respectively. The dog will then be in the form shown at the right of Fig. 10 and ready for application to a releaser. The holes 84 will be aligned and receive the pivot pin 86, and a coil spring 87 will have its upper end inserted in a hole 76 and its lower end fitted over fingers 85.

The normal effect of spring 87 is to turn the dog counter-clockwise from the position of Fig. 11, but when the releaser is down in its normal position it is held there by a spring plunger 90 usual in magazines as set forth, and a part 91 of the magazine frame engages the dog to hold it as shown in Fig. 11. When the releaser is raised spring 87 moves the bridge 81 over a shelf 92 secured to rocker shaft 35, and when the releaser is subsequently lowered the dog engages the shelf to rock the shaft counter-clockwise, Fig. 11. At a later time the shaft is returned to its normal position by well known mechanism not set forth herein. The various elements 50, 51, 62 and 67 may if desired be formed with wedges 95 similar

to wedges shown in Chevrette Patent No. 1,510,765.

From the foregoing it will be seen that the invention sets forth a bobbin releaser made of two parts or elements secured to each other with one part having a bent wing which enters a notch in the other part to position the two parts. It will also be seen that two different kinds of releasers can be made from the same pair of releaser forming elements, depending upon the direction in which the cradle operating wing is bent. Furthermore, the releaser is provided with a simple form of dog pivoted at the upper end thereof and made of a stamping which includes a bridge for operating the shelf 92 and also fingers 85 for receiving one end of spring 81. In the long releasers the lugs or fingers which cooperate with the color slide extent from one releaser forming element through notches in the other element to position the two parts.

Having thus described the invention it will be seen that changes and modifications of the foregoing specific disclosure may be made without departing from the spirit and scope of the invention.

What is claimed as new is:

1. In a bobbin releaser for a weft replenishing loom having a bobbin delivery cradle, said releaser comprising two elongated sheet metal elements arranged side by side and secured together, one of said elements having a bobbin cradle operating wing bent laterally therefrom.

2. In a bobbin releaser for a weft replenishing loom having a bobbin delivery cradle, said releaser comprising two elongated sheet metal elements arranged side by side and secured together, one of said elements having a bobbin cradle operating wing bent laterally therefrom and extending across part of the other element.

3. In a bobbin releaser for a weft replenishing loom having a bobbin delivery cradle, said releaser comprising two elongated sheet metal elements arranged side by side and secured together, one of said elements having a bobbin cradle operating wing bent laterally therefrom and the other element having a positioning notch therein through which the wing extends.

4. A pair of elements for making either right or left hand bobbin cradle operating releasers for a weft replenishing loom, said elements being made of elongated sheet metal, one of said elements having a cradle operating wing member formed in the plane thereof, said elements when arranged side by side and the wing member bent laterally in one direction relatively to the members forming a right hand releaser, and the wing member when bent laterally in the opposite direction relatively to the members forming a left hand releaser.

5. A pair of elements for making either right or left hand bobbin cradle operating releasers for a weft replenishing loom, said elements being made of elongated sheet metal, one of said elements having a cradle operating wing member formed in the plane thereof, said one element when arranged on one side of the other element with said wing member bent laterally of said elements in one direction forming a right hand releaser, and said one element when arranged on the other side of the other element with the wing member bent laterally of said elements in the opposite direction forming a left hand releaser.

6. A pair of elements for making either right or left hand bobbin cradle operating releasers for a weft replenishing loom, said elements being made of elongated sheet metal, one of said ele-

ments having a cradle operating wing member formed in the plane thereof, the other element having a notch formed therein, said one element when arranged on one side of the other element with said wing member bent in one direction across the other element and through said notch forming a right hand releaser, and said one element when arranged on the opposite side of said other element with the wing member bent in the opposite direction across said other element and through said notch forming a left hand releaser.

7. In a bobbin releaser for a weft replenishing loom having a color slide, said releaser comprising two elongated sheet metal elements arranged side by side and secured together, one of said elements having a pair of spaced fingers for the color slide bent laterally therefrom.

8. In a bobbin releaser for a weft replenishing loom having a color slide, said releaser comprising two elongated sheet metal elements arranged side by side and secured together, one of said elements having a pair of spaced fingers for the color slide bent laterally therefrom and across parts of the other element.

9. In a bobbin releaser for a weft replenishing loom having a color slide, said releaser comprising two elongated sheet metal elements arranged side by side and secured together, one of said elements having spaced positioning notches on one edge thereof and the other element having fingers bent laterally therefrom and extending through said notches for cooperation with said color slide.

10. In a bobbin releaser for a weft replenishing loom having a bobbin delivery cradle and a color slide, said releaser comprising two elongated elements arranged side by side and secured together, one of said elements having a wing member and two spaced positioning notches in one edge thereof, and the other element having fingers for cooperation with the color slide bent laterally therefrom and extending through said notches and having also a positioning notch in one end thereof, said wing member being bent laterally from said one element and extending through said last named positioning notch for cooperation with said cradle.

11. In a bobbin releaser for a weft replenishing loom having a bobbin delivery cradle and a color slide, said releaser comprising two elongated elements arranged side by side and secured together, one of said elements having a wing member on one edge thereof and two spaced positioning notches in said edge, and fingers for the color slide extending laterally from one edge of the other element and through said notches, said other element having a notch in said one edge thereof through which the wing member extends for cooperation with the cradle.

12. A pair of elements for making either right or left hand bobbin cradle operating releasers for a weft replenishing loom having a color slide, said elements being made of flat elongated sheet metal, one of said elements having fingers for the color slide formed in the plane thereof, said elements when arranged side by side with said one element on one side of the other element and the fingers bent laterally in one direction forming a right hand releaser and said elements when arranged side by side with said one element on the other side of said other element and the fingers bent laterally in the opposite direction forming a left hand releaser.

13. A pair of elements for making either right or left hand bobbin cradle operating releasers for a weft replenishing loom having a color slide,

said elements being made of flat elongated sheet metal, one of said elements having fingers for the color slide formed in the plane thereof, said elements when arranged side by side with said one element on one side of the other element and the fingers bent laterally in one direction across said other element forming a right hand releaser, and said elements when arranged side by side with said one element on the other side of said other element and the fingers bent laterally in the opposite direction across said other element forming a left hand releaser.

14. A pair of elements for making either right or left hand bobbin cradle operating releasers for a weft replenishing loom having a color slide, said elements being made of flat elongated sheet metal, one of said elements having spaced fingers for the color slide formed in the plane thereof and the other element having spaced positioning notches to receive said fingers, said elements when arranged side by side with said one element on one side of the other element and the fingers bent laterally in one direction through said notches forming a right hand releaser, and said one element when arranged on the other side of said other element and the fingers bent in the opposite direction through said notches forming a left hand releaser.

15. A pair of flat elements for making either right or left hand bobbin cradle operating releasers for a weft replenishing loom having a bobbin cradle and a color slide, one of said elements having fingers for the color slide formed in the plane thereof and the other element having a wing member in the plane thereof for said 35

cradle, said elements when arranged side by side with said one element on one side of the other element and the fingers and wing member bent laterally in opposite directions forming either a right hand or a left hand releaser, depending upon the direction of bending of said fingers and wing member relatively to their corresponding elements.

16. A pair of flat elements for making either right or left hand bobbin cradle operating releasers for a weft replenishing loom having a bobbin cradle and a color slide, one of said elements having spaced fingers in the plane thereof for the color slide and a notch therein below said fingers, the other element having spaced notches for the fingers and a wing member for said cradle in the plane thereof and below said notches, said elements when arranged side by side with said one element on one side of the other element and the fingers bent laterally in one direction through the notches in the other element and the wing member bent laterally in the opposite direction through the notch in said one element forming a right hand releaser, and said elements when arranged side by side with said one element on the other side of said other element and the fingers bent laterally in a direction opposite to said one direction through said notches of said other element and the wing member bent laterally in said one direction through the notch of said one element forming a left hand releaser.

WILLIAM A. BLANCHARD.
